UNITED STATES PATENT OFFICE.

SALVATORE FERRAGAMO, OF SANTA BARBARA, CALIFORNIA.

SURGICAL APPLIANCE.

1,399,606.

Specification of Letters Patent. Patented Dec. 6, 1921.

Application filed December 2, 1920. Serial No. 427,740.

To all whom it may concern:

Be it known that I, SALVATORE FERRAGAMO, a citizen of Italy, residing at Santa Barbara, in the county of Santa Barbara and State of California, have invented certain new and useful Improvements in Surgical Appliances; and I do hereby declare the following to be a full, clear, and exact description of the invention, such as will enable others skilled in the art to which it appertains to make and use the same.

This invention relates to surgical appliances, and more particularly stated contemplates a novel leg supporting and stretching device.

An object of the present invention is to produce a readily attached stretching device interconnected with the surgical dressing and more especially the parallel binding members or strips, whereby a direct and more effective pull is exerted upon the leg.

Another object of this invention is the production of a surgical stretching device in which a novel frame is interconnected between the surgical dressing and a pulling device, the said frame being arranged and adapted to slidably support a suitable foot form or orthopedic shoe for more effectively positioning the injured portion of the leg and foot, thereby materially adding to the comfort of the patient.

Another object of this invention is to produce a readily removable and comfortably constructed foot support or shoe, the said shoe being provided with novel means for adjustably attaching the same to the stretching frame, and arranged to move thereon independently of the movement imparted to the leg by the pulling device.

With these and other objects in view the invention further consists in the comparatively simple construction of the several parts to be more fully hereinafter described and pointed out in the appended claims.

In the accompanying drawings illustrating an embodiment of my invention, and in which similar reference characters designate corresponding parts in the several views:

Figure 1 is a perspective view of my improved apparatus shown in associated position with a surgical leg dressing;

Fig. 2 is an enlarged horizontal sectional view on the line 2—2 of Fig. 1;

Fig. 3 is a detail cross-sectional view

through turnbuckle pulling device on the line 3—3 of Fig. 2;

Fig. 4 is an enlarged sectional view through the foot support or orthopedic shoe;

Fig. 5 is a detached perspective view of the insole or foot supporting pad;

Fig. 6 is a similar view of the bar inserted within a pocket of the insole for stiffening the foot support;

Fig. 7 is a detail view of the body portion of the shoe in a developed position and prior to its attachment to the base of the shoe;

Fig. 8 is a detail view of a modified form of turnbuckle utilized to effect the stretching of the leg; and

Fig. 9 is a view of still another modified form of the pull exerting means, including a chain adapted to be twisted by an ordinary bar or rod.

The present invention has been designed with a view to materially increasing the comfort of the patient, and at the same time more effectively impart the necessary pulling or stretching force to the injured limb. This is accomplished by utilizing certain portions of the surgical dressing and preferably the longitudinal or parallel binding strips upon either side of the leg. Suitable connecting devices or rings are provided on these binding strips and it is to these rings that the stretching frame is attached. The pulling means is directly connected to the stretching frame, but as shown the foot support is independently movable with relation to the movement of the stretching frame.

This construction has been found to permit of a more accurate and beneficial adjustment of the apparatus and permit of its adaptation to a greater variety of fractures, sprains and other injuries to the leg or foot.

Referring to the drawings, the surgical dressing 1 may be of ordinary conformation according to the character of the injury, and includes the binding members or strips 2, suitably bound upon either side of the leg by a wrapping 3. This wrapping consists preferably of an adhesive material, and likewise the strips may also be of the same material.

Connecting devices 4 are secured to the ends of the strips 2, and as shown are in the form of triangular ring members se-

cured to the strips by rivets or stitching, or in any other approved manner. The arrangement of the triangular ring is such as to permit of one of its sides being secured to the strips 2, thereby allowing the other two sides to converge as shown for connection with the stretching frame 5. By this construction, the connection of the frame and binding strips serves to maintain the pull in longitudinal alinement, as will be understood.

The stretching frame 5 is preferably formed of a strap member bent in substantially a U-shape as shown, each side member of the frame being provided with an eye 6, adapted to be connected with the triangular ring 4. A ring 7 is swiveled in the cross bar of the frame 5 and has connected therewith one end of a turnbuckle 8. The opposite end of the turnbuckle is connected to any suitable support such for example as the end of a bed as shown, or it may be desirable to utilize some other means of relatively fixed support. An operating device 9 in the form of a ring 10 provided with radial arms 11 is preferably secured to the frame of the turnbuckle to facilitate its easy operation.

The foot supporting or orthopedic shoe 12 consists of a base board 13 to which is secured the body portion 14. A binding strip 15 may be used to hold the body portion in place. The body portion of the shoe may be composed of leather, rubber, or other suitable material, and is provided with fastening straps and buckles 16. An underlying shield 17 is also provided, the same being either attached to or formed integral with the body portion of the shoe. Beneath the shield 17 a relatively soft pad or pillow 18 may be inserted as will be understood. Arranged within the body portion of the shoe and forming the side walls thereof are similarly padded surfaces 19, the same being either attached to or removably positioned within the shoe. These padded surfaces or pillows 19 are provided upon both side walls of the shoe and also at the rear thereof for the easy resting of the heel as will be understood. A detachable insole 20 is co-operatively associated with the shoe and serves to add to the support of the foot and more particularly the toes. This insole is relatively large and extends beyond the base of the shoe. A pocket 21 is formed in the insole and into this pocket a bar 22 may be inserted for increasing the rigidity of the support and otherwise stiffening the extending portions of the insole. In some cases it is desirable to insert this bar and maintain the foot and toes in substantially a fixed or non-movable position, and then again the bar may be removed for permitting a certain amount of movement or flexing of the insole. In some cases the insole may be entirely re-

moved and the forward portion of the foot and toes permitted to freely move. The shoe is supported upon the frame 5 by means of connecting devices in the form of screw hooks 23, adjustably positioned within the holes 24 arranged upon each side of the shoe. The hooks are preferably screw threaded at one end and are provided with relatively long arms adapted to extend over the U-frame as shown. By this construction it will be seen that the shoe is independently movable upon the frame 5, thereby permitting of such slight longitudinal movements of the foot as may be deemed advisable for the comfort of the patient. Likewise it will be noted that the vertical position of the shoe can be adjusted, thereby further permitting of a more accurate positioning of the foot with respect to the injury. The regulations of the several supporting and stretching devices are apparent from the foregoing construction, and its simplicity of construction and application permit of its adoption with attending minimum expense. In the form of turnbuckle shown in Fig. 8 the radial arms 11^a are pivotally secured to the ring member 10^a thereby permitting of their collapse. Lips 11^b are formed on the arm 11^a as shown and limit the movement of the arm in a vertical position when operating the turnbuckle. This form of turnbuckle may be used where it is desirable to reduce the number of protruding parts of the device. In Fig. 9 another form of pulling means is disclosed wherein a chain 10^a is interconnected between the swiveled ring 7 and a suitable support 10^b. A rod or bar 10^c is inserted through a link of said chain and twisted, thereby shortening the length of the chain and creating a pulling action upon the stretching frame. This simple form may be adopted where it is desirable to give a temporary pull to the leg. From the foregoing it will be obvious that a comparatively inexpensive and at the same time highly effective stretching device has been provided capable of beneficial and substantially painless adaptation to numerous forms of injuries.

I claim:

1. A surgical appliance comprising a leg stretching frame, a supporting shoe movably associated with said frame, means for vertically adjusting the position of said shoe with respect to the frame, said means also serving to support the shoe upon the frame, and means for moving said stretching frame independently of the shoe supported thereon.

2. In a surgical supporting and stretching apparatus, the combination with a surgical dressing involving binding members arranged upon each side of said dressing, of a movable stretching frame secured to each of said binding members, a stretching means interconnected with said frame and a relatively fixed support, and a supporting shoe

provided with connecting devices slidingly positioned upon said frame whereby independent longitudinal movement between said frame and shoe may be effected, said connecting devices also serving to regulate the height of the supporting shoe within the frame.

3. In a surgical supporting and stretching apparatus, the combination with a surgical dressing involving longitudinal binding strips, of a movable U-shaped frame having side arms connected to each of said strips, a swivel connection provided in said frame, and means including a screw interconnected with said swivel and a relatively fixed support for moving the aforesaid frame.

4. A surgical appliance comprising a stretching frame having longitudinally disposed side arms and a supporting shoe mov-

ably mounted upon said arms, the said shoe being provided with an adjustable connecting device for regulating the height of said shoe and including a removable insole having a detachable stiffening member.

5. A surgical appliance comprising a leg stretching frame, a supporting shoe slidably mounted upon said frame having openings therein, and devices including pins adjustably positioned in the said openings provided in the shoe, said pins being adapted to rest upon the frame for slidably supporting the shoe thereon.

In testimony whereof I affix my signature, in presence of two subscribing witnesses.

SALVATORE FERRAGAMO.
